UNITED STATES PATENT OFFICE.

JAMES M. SHAW, OF DALLAS, TEXAS, ASSIGNOR TO MOSHER STEEL & MACHINERY COMPANY, OF DALLAS, TEXAS, A CORPORATION OF TEXAS.

PORTABLE FUEL GRATE.

Application filed March 21, 1924. Serial No. 700,804.

To all whom it may concern:

Be it known that I, JAMES M. SHAW, a citizen of the United States of America, residing at Dallas, in the county of Dallas and 5 State of Texas, have invented certain new and useful Improvements in Portable Fuel Grates, of which the following is a specification.

This invention relates to new and useful 10 improvements in portable fuel grates and particularly for burning fuel in brick kilns.

The object of the invention is to provide a portable grate for burning certain fuels, such as lignite coal and the like; and particularly a grate arranged so that the top 15 ashes or combusted products may be raked from the bed of fire, without disturbing the under side or lower stratum of said fire.

A further object is to provide a portable 20 fuel grate for burning hydrocarbon fuel of the character which requires the maintaining of an incandescent stratum contiguous to the grate bars in order to promote efficient combustion and to obtain a maximum heat.

25 A particular object is to provide a grate having guides or runners above the bars for supporting a slash bar or rake above the surface of said bars, when the fire is raked to remove the top ashes.

30 Another object is to provide a portable grate with a combination damper and drag leaf, which serves to prevent the escape of forced draft air currents from the inner end of the grate and also acts to drag out the 35 fallen ashes when the grate is pulled from the flue or passage under the kiln.

A construction designed to carry out the 40 invention will be hereinafter described, together with other features of the invention.

45 The invention will be more readily understood from a reading of the following specification and by reference to the accompanying drawings, in which an example of the invention is shown, and wherein:

Fig. 1 is a plan view of a grate constructed 50 in accordance with my invention,

Fig. 2 is a side elevation of the same,

Fig. 3 is a plan view of the slash bar,

Fig. 4 is a partial side elevation of the 55 same,

Fig. 5 is a cross-sectional view of the lower portion of a kiln showing the grate therein,

Fig. 6 is an enlarged end elevation,

Fig. 7 is a transverse sectional view on 55 the line 7—7 of Fig. 1, and

Fig. 8 is a plan view of a modified form.

In the drawings the numeral 10 designates an elongated frame having standards 11 at each side arranged in pairs and bifurcated so as to receive the trunnions of wheels 12. At the left hand or rear end (Figs. 1, 2 and 5) the frame has a pair of central standards 11' also bifurcated to receive the trunnions of a wheel 12'. A shank 13 extends from the front end of the frame and a tubular tongue 14 is fitted over and attached to the shank for pulling the grate from the kiln flue and pushing it thereinto.

The upper surface of the frame, which 70 forms the grate proper, is divided into panels by cross-bars 15 extending between and flush with the side bars of the frame. These grate panels are foraminous and may be formed of longitudinal spaced bars 16 or 75 they may be perforated as is shown in Fig. 8 at 17, or any other suitable foraminous structure may be employed.

In order to retain the fuel on the grate I 80 provide side sections or guards 18 which have their ends bevelled to fit in dove-tailed 85 sockets 19 formed on the side of the frame. An end section 20 is bevelled to fit in sockets 21 on the rear of the frame. The sections 18 and 20 have upright fingers 22 which are 90 spaced apart and extend above the frame. These fingers act as guards to prevent the fuel, such as lumps of lignite coal, from falling from the grate, but permit the ashes to discharge therebetween and also allow a 95 sufficient cross draft over the fire to promote combustion.

In burning lignite and kindred fuels, the 100 ashes must be removed from the top of the bed of the fire and to do this without disturbing the lower or incandescent stratum, is difficult of accomplishment on the ordinary grate. The disturbing or disintegration of the lower stratum is disastrous to the fire. One of the features of this invention 105 is to provide means for raking off the ashes without disturbing or disintegrating the lower or incandescent stratum.

To accomplish this I provide a pair of elevated, transversely spaced guide bars or 110 rails 23 extending longitudinally of the grate from end to end thereof. These rails extend sufficiently above the surface of the

grate bars to support the blade 24 of a slash bar 25, above the lower stratum of the bed of coals, when said bar is moved along said rails to rake the ashes from the fire. By this arrangement the ashes may be quickly and freely removed without fear of impairing the fire.

Under the rear end of the frame 10 I hinge a transverse drag plate or leaf 26, 10 which also acts as a damper when a forced draft pipe 27 is supported under the frame. The plate is slightly longer than the distance from the frame to the floor of the flue and it is held at a forward inclination 15 by lugs 27'. When the grate is pulled from the flue, the plate drags out the ashes.

Various changes in the size and shape of the different parts, as well as modifications and alterations may be made within the 20 scope of the appended claims.

What I claim, is:

1. In a fuel grate, the combination of a frame having draft openings, wheels for supporting said frame, guards at the sides 25 of said frame, and means for supporting a raking implement above the surface of the grate to preserve the lower stratum of the fire when the top ashes are removed.

2. In a fuel grate, the combination of a frame having draft openings, wheels for supporting said frame, guards at the sides of said frame, means for supporting a raking implement above the surface of the grate to preserve the lower stratum of the fire when the top ashes are removed, and a 35 drag plate under the frame.

3. The combination with the upper surface of a fuel grate for burning hydrocar-

bon fuel, of means extending longitudinally of the grate for supporting an implement 40 above the surface of the grate when raking the ashes from the top of the fire.

4. In a portable fuel grate, a wheel supported frame having grate panels, and side guard sections mounted on the frame having 45 upright spaced fingers extending above the frame.

5. In a portable fuel grate, a wheel supported frame having grate panels, and side guard sections mounted on the frame having 50 upright spaced fingers extending above the frame, said sections being detachably supported on the sides of the frame.

6. In a portable fuel grate, a wheel supported frame having grate panels, side guard sections mounted on the frame having 55 upright spaced fingers extending above the frame, and an end section mounted on the frame.

7. In a portable fuel grate, a wheel supported frame having grate panels, side guard sections mounted on the frame having 60 upright spaced fingers extending above the frame, and an end section mounted on the frame, said side and end sections being 65 detachably supported on the frame.

8. In a portable grate, the combination of a wheel supported frame having a grate surface, standards supporting the frame, wheels supporting the standards, side guards 70 on the frame, end guards on the frame, said guards having spaced portions extending above the grate surface, and raking rails elevated above the grate surface.

In testimony whereof I affix my signature.
JAMES M. SHAW.
